(57) **CLAIM**

We claim the ornamental design for a label for bottles, as shown and described.

DESCRIPTION

FIG. 1 is a front view of the first embodiment of a label for bottles, showing our new design;

FIG. 2 is a rear view thereof;

FIG. 3 is a front view of the second embodiment of a label for bottles;

FIG. 4 is a rear view thereof;

FIG. 5 is a front view of the third embodiment of a label for bottles; and,

FIG. 6 is a rear view thereof.

The broken lines in FIG. 1 show perforations that form part of the claimed design.

1 Claim, 6 Drawing Sheets
